UNITED STATES PATENT OFFICE.

FREDERICK M. BALSLEY, OF MADISON, WISCONSIN.

MARKER FOR PAVEMENTS.

Application filed October 9, 1922. Serial No. 593,465.

This invention relates to a device for marking pavements.

It is a primary object of this invention to produce a practical mechanism for applying a marking fluid to a concrete or asphalt surface. The machine is particularly adapted for use for marking upon the solidly paved surface of a highway a center line adapted to apportion the highway between vehicles bound in opposite directions thereon.

More particularly, it is the object of this invention to provide a machine which can be moved rapidly upon a highway surface to follow in a straight line the course laid out upon said surface. It is also my object to provide means for permitting the machine to be used readily on curves and to be turned around when desired.

It is a further object of this invention to provide a machine having a centralized control; to provide means for cleaning the pavement in advance of the marking roller; to provide a marking roller of peculiar construction particularly adapted for this service; and to provide means for supplying marking fluid in a manner adapted to cooperate with a marking wheel to distribute the fluid effectively and in a line upon the pavement.

In the drawings:

Fig. 1 is a plan view of a pavement marking device embodying this invention.

Fig. 2 is a side elevation of the same.

Fig. 3 is a detail section taken on line 3—3 of Fig. 2.

Fig. 4 is a detail section taken on line 4—4 of Fig. 2.

Like parts are identified by the same reference characters throughout the several views.

In appearance, the present embodiment of this invention resembles a wheelbarrow to some extent. Converging frame members 5 and 6 are provided with handles 7 at their outer and upper ends and are provided at their lower and inner ends with journals 8 adapted to receive the axle shaft 9 of the marking wheel 10 and adapted to support said frame members. This wheel can conveniently be built up of several laminations of wood, as shown more particularly in Fig. 3.

The device differs from a wheelbarrow, however, in that small supporting wheels 12 are preferably provided. These may con-

veniently be disposed at the lower extremities of vertical frame members 13. A platform 14 is supported as illustrated by means of bracing members 15 secured to the converging members 5 and 6 and to the vertical members 13.

Pivoted to the main frame of the device is a sub frame 17, the side members 18 and 19 of which constitute forwardly extending continuations of the side members 5 and 6 of the main frame. The subframe 17 is secured to members 5 and 6 at some distance to the rear of the forward ends of said members by pivot bolts 20. A lead wheel 21 which is preferably leather faced at 22 is journaled for rotation at the forward end of sub frame 17. The lead wheel is positively, although resiliently, urged in the direction of the pavement by a spring 24 confined between a bracket 25 carried by the main frame member 5 and a nut 26 upon the fitting 27 carried by the sub frame member 18. A similar arrangement may be used upon either side of the device to apply to the sub frame 17 a portion of the weight carried by the main frame and thereby to maintain the lead wheel 21 in positive contact with the pavement.

Immediately at the rear of the lead wheel 21 and immediately ahead of marking wheel 10, there is preferably provided a pavement cleaning brush 30, the handle 31 of which may conveniently be pivoted upon a transverse rod 32, as shown. Springs 33 may be utilized to draw the brush forwardly about its pivot upon transverse member 32 and thereby bring it the more effectively into contact with the road surface.

Adjacent the transverse member 32 or otherwise connected to sub frame 17, I preferably provide a cord 34 which runs over a pulley 35 supported from the main frame or from the platform thereon to a hand lever 36. When this lever is pulled rearwardly about its pivot point 37 until the cord 34 passes across the center represented by point 37, lever 36 will come to rest and will be maintained in position by a stop 38 which will resist the pull upon cord 34, tending to rotate lever 36 further in the same direction. The operation of lever 36 to the position above described in contact with stop 38 will have the effect of raising from the pavement the lead wheel 21 and brush 30.

Upon the platform 14, I provide a receptacle or tank 40 which may be secured there-

to by bolts 41 or by any other approved means, and which is adapted to receive through an opening normally closed by a cover 42 the marking fluid to be applied to 5 the road surface. From the bottom portions of receptacle 40, a pipe 43 leads forwardly. Fluid delivery through said pipe is controlled by a valve therein. The handle 44 of said valve is represented clearly in 10 Fig. 1 and is shown to be normally retained in the position in which it is illustrated in said figure by a spring 45. The valve may conveniently be opened, however, by means of a pull rod 46 extending to a position within 15 in the grasp of the operator and connected with handle 44 through the bell crank 47 and link 48. When the valve is opened by means of the pull rod 46, fluid will flow through pipe 43 and will be delivered in the 20 form of a fan shaped jet through the flaring end 48' of the pipe.

The flaring end of the pipe illustrated at 48' is downwardly curved as clearly shown in Fig. 2 and extends into close proximity to the peculiar marking pad upon the marking wheel 10. This marking pad may be positioned upon the wheel in any desired manner. In the present embodiment of my invention, I have illustrated a flanged rim 30 49 upon the periphery of wheel 10. The marking pad receivable within said rim preferably comprises a porous outer surface 50 of some material of considerable strength adapted to stand the wear occasioned by its 35 operation over road surfaces. If desired, the material 50 may comprise canvas fabric and it may conveniently be formed in a tube, as shown in Fig. 3. Within the tube, I prefer to use some absorbent and resiliently 40 compressible material, such for example, as felt. Burlap and other materials may also be used, if desired. It is my object to provide an absorbent pad adapted to receive and retain the marking fluid and to protect 45 such pad from wear by covering it as with the canvas tube shown at 50 in Fig. 3. The absorbent material is illustrated in Fig. 3 in the form of a plurality of layers 51 of felt.

50 The device of my invention is operated as follows. The periphery of the marking wheel is referred to herein as a tire irrespective of how it is constructed.

The highway is preferably marked with 55 a center line by means of a chalk line or other well known expedient for this purpose. The chalk line will serve as a guide for the mechanism above described which is adapted to put a permanent mark upon the 60 pavement.

Thereafter with the tank 40 full of marking fluid (which may comprise any one of a number of well known derivatives of tar) the mechanism is positioned at the beginning 65 of the stretch of pavement to be

marked. The leather lead wheel 21 is so positioned as to be clearly within the view of the operator who so directs the mechanism that the lead wheel will conform to the chalk line previously marked upon the 70 pavement. The small wheels 12 at the rear of the device support the weight of the rear portions of the mechanism and the operator, therefore, is required only to propel and 75 guide the device.

The device tends normally to move along a perfectly straight line. The leather covered lead wheel 21 urged by springs 24 into a positive contact with the surface of the pavement does not readily slip sidewise 80 thereon, and consequently, tends to keep the mechanism in a straight course. The brush 30 sweeps from the path of the marking wheel 10 any foreign matter which might otherwise receive the marking fluid intended 85 for the pavement.

When the device is set in motion, the pull rod 46 is pulled rearwardly by the operator and positioned by engagement with a pin or plate 53 of any one of a plurality of 90 notches 54 cut in the under side of the pull rod. The handle 44 is thereby actuated against the tension of spring 45 to an open or partially open position whereupon the fluid stored in tank 40 will be delivered 95 through the flaring end 48 of pipe 43 to the upper surface of the pad upon marking wheel 10.

As the movement of the mechanism over the highway continues, the pad upon the marking wheel will become entirely saturated with the marking fluid. The felt packing 51 within the pad serves to store and retain the fluid and to deliver it back through the canvas covering 50 when the weight of the device presses the marking pad into contact with the pavement. Obviously, the covering 50 protects from otherwise detrimental wear the soft felt or other absorbent material which retains the marking fluid.

Thus, during the forward operation of the device the liquid flowing upon the top of the marking wheel is brought by the rotation of the wheel to the pavement and is applied thereto to print upon the pavement a line or marking conforming in width to the pad upon the marking wheel and of any desired length.

When a curve in the highway is encountered or when it is desired to turn the machine around, the handle 36 will be drawn rearwardly and across center whereupon it will be brought to rest by stop 38. The sub frame 17 will thus be elevated and will lift from the pavement the lead or guide wheel 21 and the brush 30. When the curve has been rounded and substantially straight highway is again encountered, a reverse movement of handle 36 will permit the lead wheel 21 and brush 30 to drop again upon the pavement.

When the marking operation is complete, the pull rod 46 will be lifted slightly to release notches 54 from engagement with pin 53 whereupon the tension of spring 45 will close the valve by rotating handle 44 to the position in which it appears in Fig. 1.

It will be seen from the foregoing that the objects specified for this invention are fully satisfied by the device herein disclosed.

10 Various changes may be made, however, without departing from the spirit of my invention. For example, I do not wish to be limited to any particular kind of marking fluid, and obviously paint may be used, if desired, instead of a coal tar derivative. It has been my experience, however, that paint will not satisfactorily adhere to the pavement and, for this reason, the coal tar derivative is preferred.

20 The marking wheel may also be changed in structure without departing from the spirit or purpose of my invention. The wheel has been described as being provided with a peripheral absorbent pad for applying the marking fluid to the pavement, but it will be understood that the principle of applying the marking fluid by the rotation of a wheel rolling upon the paved surface is more important than the particular construction of wheel which is used to accomplish the desired result.

While the foregoing description has related solely to a manually propelled embodiment of this invention, I wish to make it clear that in a broad sense, it is immaterial to my invention whether the marking wheel be manually propelled or whether it be driven by or attached to or drawn from some other vehicle, such as a horse drawn vehicle, or a self-propelled vehicle, such as a motor truck.

I claim:

1. A pavement marking device including a frame, a marking wheel supporting said frame, a lead wheel guided by and yieldable vertically relative to said frame, resilient means acting between said wheel and frame to urge said wheel into contact with a surface traversed thereby, and a receptacle for marking fluid arranged to deliver such fluid to the periphery of said marking wheel.

2. A pavement marking device including first and second frames, wheels rotatably mounted in tandem in the separate frames, means for raising one of said frames with reference to the other, resilient means acting between said frames to oppose the relative raising of said frames and means for supplying marking fluid to the periphery of one of said wheels.

3. A pavement marking device including a main frame, a marking wheel journaled therein and adapted to contribute to the support of said frame, a sub-frame pivotally connected to the main frame about a trans-

verse axis for independent relative movement with respect to a supporting surface, a second wheel journaled in said sub-frame substantially in tandem with said first mentioned wheel, a spring acting between said frames thereby to urge said second wheel into contact with a surface traversed thereby, and means for delivering a marking fluid to said first mentioned wheel.

4. A pavement marking device including a main frame, a marking wheel journaled therein and adapted to support one end of said frame, a sub frame pivotally secured to the main frame and extending in advance thereof, a lead wheel faced with a substance adapted to adhere to the highway, said lead wheel being journaled in the sub frame in tandem with said marking wheel, and means for resiliently transferring to said sub frame a portion of the weight of said frame, whereby said lead wheel is pressed into contact with a surface traversed thereby.

5. A pavement marking device including a main frame, a marking wheel journaled therein, a sub frame pivotally secured to the main frame and resiliently urged about its pivot in the direction of the pavement, a guide wheel journaled in said sub frame and pressed therewith against the surface of the pavement, and means under the control of an operator for lifting said guiding wheel from the pavement.

6. A pavement marking device including a main frame provided with rearwardly projecting handles, a marking wheel journaled therein, a sub frame pivotally connected to the main frame, a guide wheel journaled in the sub frame, means for resiliently transferring from the main frame a portion of the weight thereof to said guide wheel through the sub frame, and a brush carried by said sub frame between the guide wheel and the marking wheel and adapted to contact with the pavement surface traversed by the device.

7. A pavement marking device including a main frame provided with guiding handles at the rear, a marking wheel journaled in said main frame, a sub frame disposed forwardly of the main frame, a lead wheel journaled in said sub frame, a brush pivotally supported from said sub frame and adapted in one position to contact with the surface of a road traversed by the device, and means for resiliently urging said brush toward said position.

8. A pavement marking device including a main frame provided with guiding handles at the rear, a marking wheel journaled in said main frame, a sub frame disposed forwardly of the main frame, a lead wheel journaled in said sub frame, a brush pivotally supported from said sub frame and adapted in one position to contact with the

surface of a road traversed by the device, means for resiliently urging said brush toward said position, and means adjacent said guiding handles for lifting said sub frame, lead wheel and brush out of operative position.

9. A pavement marking device including first and second frames in relative pivotal connection, road wheels operatively mounted in each of said frames and contributing in part to the support of their respective frames, additional wheels operatively connected with said first frame and contributing to the support thereof in positions to maintain said first frame in equilibrium, said second frame being provided with support through its pivotal connection with the first frame as well as through its road wheel, a receptacle for marking fluid mounted upon one of said frames, and means communicating with said receptacle and arranged to direct said marking fluid upon one of said first mentioned road wheels.

10. A pavement marking device including a marking wheel, means for propelling said wheel, an absorbent pad peripherally disposed

about said wheel, flexible and porous means for protecting said pad from disintegration, and means for supplying to said wheel during the rotation thereof of a marking fluid adapted to penetrate said porous protecting means to reach said pad.

11. A marking device including a frame, a marking wheel journaled for rotation upon a pavement or surface to be marked, a tire comprising an absorbent pad sheathed in fabric and disposed about the periphery of said wheel, means above said wheel for supplying a marking fluid to its periphery during its rotation, and means for controlling the supply of fluid to the wheel.

12. In a device of the character described, a marking wheel comprising a peripherally flanged wheel and a tire positioned by said flange and comprising an absorbent substance sheathed in fabric.

13. In a device of the character described, a marking wheel provided with a flanged periphery and a peripheral felt pad positioned by said flange and provided with a canvas sheath.

FREDERICK M. BALSLEY.
